L. RINEHART

DRAIN PLOW

Filed July 8, 1921

Patented May 29, 1923.

1,457,271

UNITED STATES PATENT OFFICE.

LORON RINEHART, OF WOODBURN, OREGON.

DRAIN FLOW.

Application filed July 8, 1921. Serial No. 483,359.

To all whom it may concern:

Be it known that I, LORON RINEHART, a citizen of the United States, residing at Woodburn, in the county of Marion and State of Oregon, have invented new and useful Improvements in Drain Plows, of which the following is a specification.

This invention relates to an improved drain plow and has for its principal object 10 to provide an implement which may be drawn by either horse or tractor for producing underground drains in farm lands, to take the place of the present known expensive methods of caring for the drainage of 15 lands.

A further object of my invention is to so construct the implement that it will produce a perfect drain without cutting up the ground surface of the field or otherwise interfering with the tilling of the land.

A still further object of my invention is to provide means for producing a drain beneath the ground surface deep enough to prevent the same from caving in even when 25 stock walk over it and in this connection the drain should be so formed that it will last over a period of years thus removing the expense in opening up the drains every year or oftener as is now the case.

Another object of this invention is to 30 provide a device of the character described which is simple in construction, positive in action, economical to manufacture and highly serviceable.

Other objects and advantages will be apparent during the course of the following description.

In the accompanying drawings forming a 40 part of this specification and in which like numerals are employed to designate like parts throughout the same,

Figure 1 is a view in side elevation of my improved implement,

Fig. 2 is a horizontal section on the line 45 2—2 of Figure 1,

Fig. 3 is a cross section on the line 3—3 of Fig. 4 of the drill which I use for forming the underground drain, and

Fig. 4 is a longitudinal section on the line 50 4—4 of Fig. 2.

In the drawings wherein for the purpose of illustration is shown a preferred embodiment of my invention the numeral 1 designates a draft bar having a clevis connection 55 2 for towing purposes and with handle bars 3 mounted to the rear of the bar 1 and

braced therefrom by the brace rods 4. Carried upon the rear top side of the bar 1 is a toothed segment 5 which includes a suitable supporting structure 6 having legs 60 which are bolted or otherwise fixed to the bar as best shown in Fig. 1. The supporting structure also includes a horizontal bridge piece 7 which provides a mounting for the pivot 8 of the operating lever, 9. This lever 65 has a spring controlled dogging device 10 which is actuated by the rod extension 11 having a hand grip 12 which is gripped by the operator when handling the lever so that the lever may be released and swung forward or backward when occasion demands. 70

Formed preferably as a part of the lever 9 is an extension arm 13, the same being pivoted as at 8 and extending at right angles from the lower end of the lever in a bell 75 crank fashion. Pivoted as at 14 to the end of the arm 13 is a vertical rod 15 the lower end of which is received in an elongated slotted opening 16 in the top of the drill 17 and pivotally connected within the hollow of the 80 drill by the transverse pin 18. This rod thus acts as a toggle connection between the drill and the control lever 9.

The forward part of the drill is suspended 85 from the knife standard 19 by the pivoted connection afforded by the pin 20 and with the end of the standard entering the hollow of the drill through the opening 21 in the top thereof, as in the case of the rod 15. The opposite end of the standard is 90 hung from the underside of the draft bar by its bifurcated mounting end 22. Both of the pins 18 and 20 are carried by arcuate or semi-circular plates 23 and 24 which are 95 bolted to the inside of the drill in confronting relation so that the attached ends of the rod 15 and standard 19 may be confined by the pins 18 and 20 or bolts if desired.

The drill as above described is mounted 100 below the draft bar 1 in a substantially horizontal position with the lever 9 adapted to be moved to change the horizontal plane in which it is intended to function by tipping its pointed end 25 up or down so that the depth of the drain under the ground surface may be changed. The pointed end 25 is preferably solid and threaded to the hollow drill body so that it may be removed for sharpening or renewed by a new point. The bevel of the sides of the point are also made 110 at slightly different angles to the horizontal axis of the drill, as will be seen to more

effectively produce the drain and at the same time keep the drill from coming out of the ground.

To relieve resistance to the draft of the 5 implement the standard 19 is arranged with a knife edge 26 along its vertical front edge.

It is to be understood that the form of my 10 invention herewith shown and described is to be taken as a preferred example of the same, and that various changes in the shape, size and arrangement of parts may be resorted to without departing from the spirit 15 of the invention or the scope of the subjoined claim.

Having thus described my invention, I 15 claim:—

In an implement of the class described, a drill adapted to be pulled through the ground beneath the surface thereof in sub-

stantially a horizontal position, a mounting 20 for the drill having draft connecting means and means for manually changing the horizontal angular position of the drill without withdrawing the same from beneath the ground surface, comprising a standard suspended below the said mounting and having a pivoted connection with the forward part 25 of the drill and a manually controlled lever on the mounting including a vertically actuated rod with one end of the rod pivotally connected to the drill rearwardly of said standard, and the opposite end of the rod connected to said lever by a bell crank, said drill comprising a hollow cylindrical body 30 with a solid pointed nose detachably connected to the body.

In testimony whereof I affix my signature.

LORON RINEHART.
